(57) **CLAIM**

The ornamental design for a cosmetics container as shown and described.

DESCRIPTION

FIG. 1 is a front, right, top perspective view of a cosmetics container showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in FIG. 7 enclose portions of the cosmetics container that form no part of claimed design.
